UNITED STATES PATENT OFFICE.

EDWARD G. KLINGBEIL, OF LANDER, WYOMING.

HEATING-DRUM.

1,345,603.

Specification of Letters Patent.

Patented July 6, 1920.

Application filed April 23, 1919. Serial No. 292,051.

To all whom it may concern:

Be it known that I, EDWARD G. KLINGBEIL, a citizen of the United States, residing at Lander, in the county of Fremont and State of Wyoming, have invented certain new and useful Improvements in Heating-Drums, of which the following is a specification, reference being had to the accompanying drawings.

10 This invention relates to certain improvements in heating drums, and it is an object of the invention to provide a novel and improved device of this general character which may be assembled with convenience and facility and which comprises separable parts to facilitate the cleansing thereof.

Another object of the invention is to provide a novel and improved device of this general character wherein the products of 20 combustion are caused to travel therethrough in an irregular path to assure the desired heat radiation and to prevent soot or the like passing out through the flue or chimney proper.

25 An additional object of the invention is to provide a novel and improved drum of this character wherein the products of combustion may be caused to travel therethrough in an irregular path or in substantially a 30 direct path in accordance with the seasons of the year.

The invention consists in the details of construction and in the combination and arrangement of the several parts of my improved heating drum whereby certain important advantages are attained and the device rendered simpler, less expensive and otherwise more convenient and advantageous for use, as will be hereinafter more 40 fully set forth.

The novel features of my invention will hereinafter be definitely claimed.

In order that my invention may be the better understood, I will now proceed to describe the same with reference to the accompanying drawings, wherein:

Figure 1 is a vertical sectional view taken through a heating drum constructed in accordance with an embodiment of my invention and in applied position, the coacting stove being shown in fragment, and

Fig. 2 is a sectional view taken substantially on the line 2—2 of Fig. 1.

As herein disclosed, my improved drum 55 comprises two separable sections constitut-

ing the bottom section B and the top section T.

The bottom section B is cylindrical in form with its lower end closed by the head 1 and having its opposite end open, and the top section T is also cylindrical in form with its lower end open and its upper end closed by the head 2. The lower portion of the top section T telescopically engages within the upper or open end of the bottom section B and said top section T is of a length materially in excess of the corresponding dimension of the bottom section B.

At one side of the axial center thereof, the head 1 of the bottom section B is provided with an induction opening 3 defined by an upstanding flue F of a length to terminate below but in close proximity to the head 2 of the top section T when the sections B and T are in assembled relation.

The head 1 of the bottom section B in radial alinement with the flue F and at the opposite side of the axial center of said head 1 has suitably secured thereto the lower portion of a flue F'. The flue F' extends upwardly substantially in parallelism with the flue F and is of a length to telescopically engage within the lower end portion of a sleeve or thimble S disposed through the head 2 of the top section T.

The sleeve or thimble S extends above and below the head 2 and the upper portion thereof is adapted to be coupled in a conventional manner with a stove-pipe or flue of a conventional type. The lower end portion of the flue F is adapted to telescopically receive a flange 4 or the like defining the discharge opening in a stove top for the products of combustion.

The lower or connected end portion of the flue F' is provided in a wall thereof with an opening 5 while the overlying portions of the flue F and the sleeve or thimble S are provided with the registering openings 6. The registering openings 6 are under control of a damper 7 arranged within the flue F' and under control of the operating member M extending exteriorly of the drum through the head 1 of the bottom section B. The openings 6 are positioned adjacent the inner end of the flue F and said openings 6 are of a diameter to extend inwardly of the inner end of the flue F whereby a direct draft may be had from the inner end of

the flue F through the opening 6 when the damper 7 is in open position.

- In practice, the products of combustion from the stove pass upwardly through the flue F into the drum as afforded by the sections B and T and when the damper 7 is in closed position, said products of combustion pass downwardly of the drum and into the flue F' through the lower opening 5 and pass outwardly through the flue F'. This irregular travel of the products of combustion assures an effective radiation of the heat from the drum and also serves to materially eliminate the passage of soot or the like outwardly through the flue F'. Such soot or the like is generally collected upon the head 1 of the bottom section B, with the result that the heat within the drum substantially entirely consumes such deposits.
- By having my improved drum formed of separable sections, it will also be apparent that, when desired, the same may be conveniently and effectively cleansed.

When my improved drum is in use during the summer months, it is desired that the damper 7 be moved into open position so that the products of combustion will travel in substantially a direct path through the flue F and into the flue F' through the registering openings 6 with the result that the radiation of heat from the drum is materially reduced.

From the foregoing description, it is thought to be obvious that a heating drum constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting

myself to the precise arrangement and formation of the several parts herein shown in carrying out my invention in practice except as hereinafter claimed.

I claim:

A heating drum of the class described comprising two separable sections having their outer ends closed, the closed end of one of the sections being provided with a pair of radially spaced flues, and at opposite sides of the axial center of the section, one of said flues being in communication with an induction opening in the closed end of said section, said flue being of a length to terminate inwardly of the closed end of the second section when said sections are assembled, the second flue being provided with openings in its wall adjacent the opposite ends of the flue, a thimble disposed through the closed end of the second section and in which an end portion of the second flue telescopically engages when the sections are assembled, said thimble being provided with an opening registering with the opening within said end portion of the second flue, the registering openings of the thimble and second flue being positioned adjacent the inner end of the first named flue, said openings being of a diameter to extend inwardly of said inner end of the first flue, a damper within the second flue for controlling said registering openings, and means extending through said second flue and exteriorly of the drum through the closed end of the first section for operating the damper.

In testimony whereof I hereunto affix my signature in the presence of two witnesses.

EDWARD G. KLINGBEIL.
